UNITED STATES PATENT OFFICE.

ARTHUR GAMWELL, OF LOS ANGELES, CALIFORNIA.

THUMB LOCK.

Application filed May 2, 1922. Serial No. 557,990.

To all whom it may concern:

Be it known that I, ARTHUR GAMWELL, a citizen of the United States, residing at Los Angeles, in the county of Los Angeles and State of California, have invented certain new and useful Improvements in Thumb Locks, of which the following is a specification:

My invention relates to locks for holding prisoners by their thumbs and the objects are, first, to provide a means for holding the hands together to prevent escape and offense; second, to provide a thumb lock that will be small in proportions, easy to snap on the thumbs, and simple to construct; third, to provide a combination lock that has key controlled latch levers with a safety dog therebetween:

A further object of my invention is to provide an apparatus that is too small and light for use by prisoners as a weapon.

Referring to the drawing Figure 1 represents a top view of my thumb lock in its actual size:

Figure 2 represents a side view of Figure 1.

Figure 3 represents a fragmentary top view of my thumb lock in enlarged proportions.

Figure 4 represents a sectional view on line 4—4 of Figure 3.

Figure 5 represents a part sectional view on line 5—5 of Figure 4, with parts removed.

Referring to the drawing in which like characters of reference designate similar parts, the top and bottom plates 1 and 1^a respectively are secured together, with the spacers 2 and 3 in the outer central portions thereof, the arms 4 are integral with the said plates 1 and 1^a and reach semicircularly from the two end portions thereof to the joints 24, the said joints 24 are positioned in the outer end portions of the arms 4 and the fingers 5, the said fingers 5 are operatively positioned between the arms 4 and the plates 1 and 1^a, the said fingers 5 reach semicircularly from the joints 24 to the free inner ends thereof, the teeth 12^a are formed in the outer circular faces of the fingers 5, and extend back therefrom a distance with the joints 24 as the axis thereof, the latches 6 are operatively positioned on the pins 21, and the pins 21 are in turn secured in the plates 1 and 1^a, the teeth 12

are formed in the upper-outer end portions

of the latches 6 and mesh with the teeth 12^a when pressed together, the shoulders 18 are formed in the upper-inner end portions of the latches 6, and the flanges 14 are integral with the latches 6 and extend therefrom on the inner-lower portions to the cams 15, the cams 15 are integral with the said flanges 14 and are formed to suit a key positioned thru the holes 11, the said holes 11 pass thru the said top and bottom plates 1 and 1^a respectively, the springs 9 are positioned between the outer-lower portion of the flanges 14 and the inner portion of the flanges 13, the flanges 13 are integral with the said spacer 3 and extend upwardly a distance adjacent to the teeth 12^a on the fingers 5. The dog 7 is operatively positioned on the pins 20 and 8, thru the slot 19 and the spacer 2 respectively, the slot 19 passes thru the dog 7 with the longer diameter thereof lying on the center line of the dog 7, and the pin 8 is in turn secured to the upper-central portion of the dog 7 and extends upwardly therefrom on the said center line thereof, the arms 17 are integral with the two sides of the dog 7 and extend therefrom a distance over the said latches 6, the shoulders 18 are formed in the two sides of the dog 7 at points 85 below the arms 17 to fit in the corresponding shoulders 18 in the said latches 6, the cam 16 is integral with the lowermost-central portion of the dog 7, and is formed to suit the key positioned thru the said holes 11. 90

The slot 26 is formed in the upper-side face of the dog 7, adjacent to the plate 1^a, and extends from one side thereof to the other, the spring 10 is preferably elliptic in form and is positioned in the slot 26, and bears 95 slidably against the said plate 1^a.

The slide 22 is operatively secured on the outer surface of the spacer 2 by the pin 23 and over the said pin 8, the bevel face 25 is positioned adjacent to the said pin 8, and bears 100 slidably thereover, the said pin 23 passes operatively thru the slot 27 and is in turn secured to the spacer 2, and the slot 27 passes thru the said slide 22 with the larger diameter thereof in line with the travel 105 thereof.

To fasten my lock on a prisoner's thumbs, the teeth 12 in the latches 6 are first released from the teeth 12^a in the fingers 5, by inserting a suitable key thru the holes 11 in the plates 1 and 1^a, the said key is then turned to lift the cam 16, against the sliding resist-

ance of the spring 10, to release the shoulders 18 in the dog 7 from the shoulders 18 in the latches 6, and when the said shoulders 18 are released from one another, the cam 15 is in turn moved downwardly against the tension of the spring 9, to swing the latch 6 on the pins 21 to release the said teeth 12 from the teeth 12^a.

10

The dog 7 slides up on the pins 20 and 8, in the slot 19 and spacer 2 respectively, when the cam 16 is lifted to release the said shoulders 18 from one another, and the arms 17 limit the downward movement of the said dog 7, by striking on the top faces of the latches 6.

When the dog 7 is in its raised position free from the latches 6, the prisoners' thumbs are placed between the arms 4 and the fingers 5, the said fingers 5 are then closed by swinging on the joints 24 between the plates 1 and 1^a, and the arms 4, to mesh the teeth 12^a in the said fingers 5, into the teeth 12 in the said latches 6, to slidably pass over one another to grip the thumbs. It will be seen that when the teeth 12^a slide over the teeth 12, when gripping the thumbs, the latches 6 will swing on the pins 21, when the bevel faces between the said teeth 12^a and 12 slide over one another, to give the desired grip around the thumbs as hereinbefore described, and the fingers 5 are then held in place by backing the projecting faces together which are positioned between the said bevel faces in the teeth 12^a and 12 respectively.

After the thumbs are locked in place as hereinbefore described, the latches 6 are prevented from backing away from the fingers 5 when meshing the shoulders 18 together by

lowering the dog 7 on the pins 19 and 8. 40
The dog 7 is lowered by moving the bevel faces 25, in the slide 22 sideways over the outer end portion of the said pin 8.

45
The slide 22 prevents the prisoner from raising the pin 8 to release the dog 7 from the shoulders 18, and the flanges 13 also prevent probing into the inner working parts of the said lock.

Having thus described my invention, I 50
claim:

1. A thumb lock of the class described, comprising a body portion in combination with a set of extended arms positioned on each end thereof, a pair of swinging fingers adapted to be positioned between the said extended arms, toothed latches adapted to engage with the said swinging fingers, a dog adapted to hold the said latches in a locked position, a releasing means adapted to disengage the said dog from the toothed latches 60
and the said toothed latches from the swinging fingers, as set forth. 55

2. A thumb lock of the class described, comprising a central enclosed housing, arms extending from two sides of the said housing, fingers operatively positioned in the end portions of the said arms, latches adapted to slidably engage with the said fingers, a dog adapted to hold the said latches locked with the said fingers, a releasing means adapted to disengage the said dog from the said latches, a key adapted to release the said latches from the said fingers, a guard means adapted to prevent picking the said lock, as 70
set forth. 75

In testimony wherof I affix my signature.

ARTHUR GAMWELL.
